Puck and B. Owen
ATTORNEY.

UNITED STATES PATENT OFFICE.

LOUIS P. VOGTMAN, OF PARK RAPIDS, MINNESOTA.

STOVEPIPE COUPLER.

Application filed June 25, 1921. Serial No. 480,331.

To all whom it may concern:

Be it known that I, LOUIS P. VOGTMAN, citizen of the United States, residing at Park Rapids, in the county of Hubbard and 5 State of Minnesota, have invented certain new and useful Improvements in Stovepipe Couplers, of which the following is a specification.

The invention has reference to couplers 10 for pipes and more particularly to means for fastening sections of a stove pipe together in such a way as to prevent the sections from pulling apart at the joints, thereby eliminating all danger of fire and destruction of 15 property from escaping sparks and live coals.

An additional object is to provide pipe coupling means of an improved character 20 which will keep the pipe from sagging if run horizontally along a ceiling or other support and which will eliminate the hazardous risk of the old loose-joint pipe.

With the above and other objects in view the invention may be said to reside generally 25 in the details of construction, combination and arrangement of parts as will be herein-after more fully pointed out and described, reference being had to the accompanying drawings wherein:

30 Figure 1, is a front view of the invention as applied to a pipe joint; Figure 2, is a side view illustrating the manner in which the separable fasteners engage, one with the other; Figure 3, an enlarged sectional view 35 of the locking elements of the coupler; and Figure 4, a plan view of one of the fastening buckles.

In the drawings, 1 and 2 indicate sections 40 of a pipe having their adjacent ends telescoped to provide a joint, as may be seen to advantage in Figure 3 of the drawing. In applying the invention to the joints, each pipe section is provided on opposite sides with a strap-loop 3 which may be riveted or 45 otherwise fastened to the section as indicated at 4. To strap 3 of pipe section 1 are connected buckles 5 while strap 3 of pipe section 2 carries the eye members 6 engageable by the buckles for locking the sections 50 together at the joints. As the fastening means on both sides of the pipe are similar 55 means on both sides of the pipe are similar a description of one will suffice for both.

As will be seen from Figure 4 of the

drawings, buckle 5 consists of a plate 7 loosely supported by strap 3 and bifurcated 55 at one end to provide spaced parallel lugs 8, between which extends a centrally located spring tongue 9. This spring is adapted to bear upon and tension the clasp member 10 of the buckle when the latter is thrown 60 to locking position, as shown in Figure 3, the rear end 11 of the clasp being pivotally supported between lugs 8 and under spring tongue 9 as shown. The eye member engageable with clasp member 10 of the buckle 65 may consist of an elongated plate loosely joined to strap 3 of pipe section 2 and provided with a plurality of laterally spaced openings 12 extending transversely of the plate and forming eyes through which clasp 70 10 may be inserted. When the buckles and eyes of the pipe sections are relatively fastened, they project across the joint of the pipe and tend to hold the sections more firmly and positively engaged, thus preventing 75 the sections from pulling apart or becoming loosened at the joints. Since the fasteners are on opposite sides of the joints, the sections are held in proper alignment 80 and prevented from sagging even should the pipe be disposed horizontally along a ceiling or other support. Spring 9 of the buckle tends to hold clasp 10 in locking position 85 and thereby prevent accidental separation of the fastening elements. To connect the sections, clasp 10 of each buckle fastener is run forwardly of plate 7 as shown in Figure 4 so that it will be free to engage anyone of 90 openings 12 in eye plate 6, subsequent to which it may be thrown to locking position 95 as shown in Figure 3, thereby causing the pipe section to be firmly joined together.

The foregoing description and accompanying drawings have reference to what might be considered to be the approved or preferred form of my invention. I desire it to be understood, however, that I may make such changes in the construction, combination and arrangement of parts, material dimensions, et cetera, as may prove expedient 100 and fall within the scope of the appended claims.

Having thus described my invention, what I claim as new and desire to secure by Letters Patent is:

1. A pipe coupler comprising pipe sec-

tions having adjacent ends telescoped to provide a joint, separable fasteners, and means comprising loop straps for radially hinging one separable fastener to each pipe section.

2: A pipe coupler comprising pipe sections having adjacent ends telescoped to provide a joint, separable fasteners connecting the sections from opposite sides of the joint,

and loop straps for hinging the separable 10 fasteners, one each to each pipe section.

In testimony whereof I have affixed my signature in presence of two witnesses,

LOUIS P. VOGTMAN.
